TRANSPARENT COVERING PANEL FOR LIGHT FITTINGS

Friedrich Clostermann, Hagen, Germany, assignor to
Trilux-Lenze KG, Neheim-Hüsten, Germany

Filed July 11, 1969, Ser. No. 18,174

Claims priority, application Germany Jan. 15, 1969

Term of patent 14 years

Int. Cl. D26—06

U.S. Cl. D48—16

Fig. 2

Fig. 1

Fig. 3

Fig. 4

FIG. 1 is a top plan view of a transparent covering panel for light fittings showing my design;

FIG. 2 is a side elevational view looking in the direction of the arrow 2 in FIG. 1;

FIG. 3 is a fragmentary side elevational view looking in the direction of the arrow 3 of FIG. 1; and

FIG. 4 is an enlarged fragmentary top plan view of the panel showing the portion enclosed in broken lines in FIG. 1.

I claim:

The ornamental design for a transparent covering panel for light fittings, as shown and described.
